CLAIM

The ornamental design for a weight plate, as shown and described.

DESCRIPTION

FIG. 1 is a top, front, left perspective view of a weight plate showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The contrast in shading in FIGS. 1-7 represents a contrast in appearance only and does not represent any particular color, material, texture, or finish. The broken lines shown in the drawings depict portions of the weight plate that form no part of the claimed design.
